J. Miller
Atty.

UNITED STATES PATENT OFFICE.

HENRY S. MILLER, OF WASHINGTON, DISTRICT OF COLUMBIA.

PERFORATING-RULE.

1,351,002.

Specification of Letters Patent. Patented Aug. 24, 1920.

Application filed March 22, 1919. Serial No. 284,458.

To all whom it may concern:

Be it known that I, HENRY S. MILLER, a citizen of the United States, residing at Washington, in the District of Columbia, 5 have invented certain new and useful Improvements in Perforating-Rules, of which the following is a specification.

This invention relates to improvements in what are termed perforating rules, particularly applicable for use in connection 10 with the well-known printing plate-holders.

The invention has for its object, especially to provide for the effective and ready retention of the perforating rule in the plate-holder, as against the casual or inadvertent displacement of said perforating rule, also to provide for carrying out that end in a simple and inexpensive manner and with facility.

Further objects of the invention will be 20 apparent and appreciated as the nature, construction and operation thereof are disclosed from the following description or explanation taken in connection with the accompanying illustration.

25 The invention therefore consists of certain instrumentalities and features of construction substantially as hereinafter more fully set forth and pointed out in the appended claims.

30 In the accompanying drawing is illustrated the preferred embodiment of my invention wherein it will be understood that various changes and modifications as relate to the detailed construction and arrangement of parts may be made without departing 35 from the spirit or scope of the claims, and in which drawing

Figure 1 represents a side elevation of my improved perforating rule.

40 Fig. 2 is a plan view of a locking element or device particularly designed for the securing of the perforating rule in the "base."

Fig. 3 is a longitudinal section of said locking device taken on the line 3—3 of 45 Fig. 2.

Fig. 4 is a section of the same taken on the line 4—4 of Fig. 2.

Fig. 5 is a fragmental plan view showing 50 my invention in operative relation with the usual printing plate-holder.

In carrying out my invention I employ a perforating rule 1, having the general toothed or ratchet formation 1^a as shown, which is formed or made in one piece with 55 its base 2, end-posts 3 and intermediate posts 4, the posts, both end and interme-

diate, being formed with lateral studs 5. These posts, which project or depend from the lower side of the base 2 of the rule 1, are of suitable dimensions to accommodate the 60 positioning of the same within the slots in the printing plate-holder, for example, as shown, so as to allow the perforating rule proper to rest upon the printing plate-holder and to be manipulated in suitably 65 ruling or perforating the paper to be operated upon. The end-posts, with their studs or projections, are relatively arranged with respect to the rule and its base to provide for said rule snugly overlapping adjacently 70 positioned printing plate-holders. The studs 5 of the posts 4 are positioned thereon and adapted to project therefrom so as to enter the slots 4^a of the plate-holder 4^b and retain the rule effectively in position there- 75 in, a space between the base 2 of the rule and the studs 5 of the end-posts being adapted to provide for automatic interengagement thereof for the securing of these parts fast together. 80

As disclosed by Figs. 2, 3 and 4, means are shown for locking the device in the plate-holder, when necessary, which includes principally a preferably T-shaped element 6 positioned in a slot of said plate-holder. 85 A screw-threaded bore extends continuously through the stem of the T and the head thereof and within said bore works a screw 7, which screw is adapted to be actuated by a mill-edged nut 8 by suitably manipulating 90 the latter. Provided at each end of the head or cross portion of the element 6 is a latch 9 adapted, by suitably actuating said latches, to cause them to extend beyond the top edges of said cross-head portion, suffi- 95 cient space being provided for the reception of said top-edge of the cross-head of the T member or element within the slot or groove of the plate-holder. The screw 7 is provided with a head 7^a having a socket 10 for engage- 100 ment therewith of a stud 5 of a post 4 of the rule-base 27 as disclosed particularly by Fig. 5, thus providing for the retention of the rule in effective position. As above indicated, is shown the usual printing base 4^b which it 105 is believed needs no elaboration herein.

Having thus fully described my invention what I claim is—

1. A device of the type described includ- 110 ing a perforating rule provided with de- pending posts having laterally extending studs, said posts and studs being adapted to

engage a printing plate-holder base, and slots therein, respectively.

2. A device of the type described, including a perforating rule provided with pending posts having laterally projecting studs adapted to engage a printing plate-holder base, said posts being adapted to be received within slots in said base, and a locking device for said rule comprising a T-

shaped element having a screw-threaded 10 member extending therethrough, and provided with latches in its cross-head portion, said screw-threaded member being provided with an apertured head adapted for engagement with said studs. 15

In testimony whereof I affix my signature.

HENRY S. MILLER.
